**INSULATED BOX ASSEMBLY WITH
OVERLAPPING PANELS****CROSS-REFERENCE TO RELATED
APPLICATIONS**

This application is a continuation of U.S. patent application Ser. No. 17/492,285, filed Oct. 1, 2021, which issued as U.S. Pat. No. 11,724,851 on Aug. 15, 2023, which is a continuation of U.S. patent application Ser. No. 16/879,811, filed May 21, 2020, which issued as U.S. Pat. No. 11,203,458 on Dec. 21, 2021, which is a continuation of U.S. patent application Ser. No. 16/382,710, filed Apr. 12, 2019, which issued into U.S. Pat. No. 10,858,141 on Dec. 8, 2020, which claims the benefit of U.S. Provisional Application No. 62/760,672, filed on Nov. 13, 2018, which are each hereby incorporated by reference herein in their entireties.

JOINT RESEARCH AGREEMENT

The subject matter disclosed was developed and the claimed invention was made by, or on behalf of, one or more parties to a joint research agreement between MP Global Products LLC of Norfolk, Nebr. and Pratt Retail Specialties, LLC of Conyers, Ga., that was in effect on or before the effective filing date of the claimed invention, and the claimed invention was made as a result of activities undertaken within the scope of the joint research agreement.

TECHNICAL FIELD

This disclosure relates to foldable boxes. More specifically, this disclosure relates to insulated foldable boxes.

BACKGROUND

Home delivery of food is becoming more common as the process becomes more efficient and costs go down. Delivery boxes may alternatively need to keep the food hot or cold enough to, for example, prevent bacterial growth, prevent melting or congealing of the food, or simply maintain the edibility, texture, and flavor of the food. Another consideration for the type of box to use is its impact on the environment, as it relates to the reusability and recyclability of the boxes. Polystyrene foam boxes are prevalent in the food-delivery industry because of their low cost, but they are not commonly recycled. Thus, they take up a disproportionate volume of landfill space.

SUMMARY

It is to be understood that this summary is not an extensive overview of the disclosure. This summary is exemplary and not restrictive, and it is intended neither to identify key or critical elements of the disclosure nor delineate the scope thereof. The sole purpose of this summary is to explain and exemplify certain concepts of the disclosure as an introduction to the following complete and extensive detailed description.

Disclosed is a box assembly comprising an exterior piece comprising a middle portion; a connecting segment coupled to the middle portion by a fold line; and a end segment coupled to the connecting segment by a fold line, the connecting segment positioned substantially perpendicular to the middle portion and the end segment; an interior piece positioned within the exterior piece, the interior piece comprising a side panel, a space defined between the middle

2

portion and the side panel, the interior piece defining a cavity, the end segment extending into the cavity, the end segment coupled to the side panel; and an insulator positioned at least partially within the space.

Also disclosed is a method of assembling a box assembly comprising folding a lower portion of an exterior piece about a fold line relative to a middle portion of the exterior piece; folding a side panel of an interior piece about a fold line relative to a bottom panel of the interior piece; positioning an insulator within the exterior piece; positioning the interior piece within the exterior piece comprising positioning the bottom panel over the lower portion; and forming a space between the middle portion and the side panel, the insulator at least partially positioned within the space; folding a connecting segment of the exterior piece about a fold line relative to the middle portion to at least partially cover the space; inserting an end segment of the exterior piece into a cavity defined by the interior piece, the end segment coupled to the connecting segment by a fold line; and coupling the end segment to the side panel.

Also disclosed is a box assembly comprising an exterior piece comprising a first middle portion, a second middle portion, a third middle portion, and a fourth middle portion; the first middle portion and the third middle portion positioned perpendicular to the second middle portion and the fourth middle portion; a plurality of insulator pads comprising a first side insulator pad, a second side insulator pad, and a third side insulator pad; the first side insulator pad contacting the first middle portion; the second side insulator pad contacting the first middle portion, the second middle portion, and the third middle portion; the third side insulator pad contacting the third middle portion; and an interior piece positioned within the exterior piece, the interior piece comprising a first side panel and a second side panel; the first side insulator pad positioned between the first side panel and the first middle portion; the second side panel extending between the second side insulator pad and each of the first side insulator pad and the third side insulator pad.

Various implementations described in the present disclosure may include additional systems, methods, features, and advantages, which may not necessarily be expressly disclosed herein but will be apparent to one of ordinary skill in the art upon examination of the following detailed description and accompanying drawings. It is intended that all such systems, methods, features, and advantages be included within the present disclosure and protected by the accompanying claims.

BRIEF DESCRIPTION OF THE DRAWINGS

The features and components of the following figures are illustrated to emphasize the general principles of the present disclosure. Corresponding features and components throughout the figures may be designated by matching reference characters for the sake of consistency and clarity.

FIG. 1 shows a blank configured to be assembled into an exterior piece of an insulated box in accordance with one aspect of the present disclosure.

FIG. 2 is a perspective view of the exterior piece of the insulated box assembled from the blank of FIG. 1.

FIG. 3 shows a side view of insulator pads configured to be placed between an interior piece of the insulated box and the exterior piece, according to another aspect of the present disclosure.

FIG. 4 is a perspective view of the insulator pads placed inside the exterior piece.

FIG. 5 shows a blank configured to be assembled into the interior piece of the insulated box.

FIG. 6 is a perspective view of the blank of FIG. 5 with flaps of the blank slightly folded up.

FIG. 7 is a perspective view of the interior piece positioned into the exterior piece with the insulator pads of FIG. 4 positioned therebetween.

FIG. 8 is a perspective view of a top interior corner of the interior piece, with an upper portion of the exterior piece folded over to overlap a top edge of the interior piece.

FIG. 9 is a perspective view of the partially assembled insulated box, with another upper portion of the exterior piece in the process of being folded over to overlap the top edge of the interior piece.

FIG. 10 is a perspective view of the insulated box after another upper portion of the exterior piece has been folded over to overlap the top edge of the interior piece.

FIG. 11 is a perspective view of an interior of the insulated box with the upper portions of the exterior piece folded over and overlapping side panels of the interior piece.

FIG. 12 shows a blank configured to be assembled into a box insert with vertical rails in accordance with another aspect of the present disclosure.

FIG. 13 is a perspective view of the blank of FIG. 12 with rails folded slightly upwards.

FIG. 14 is a perspective view of the insert with vertical rails inside the insulated box.

FIG. 15 is a perspective view of the insert with vertical rails in accordance with another aspect of the present disclosure.

FIG. 16 is a top view of a register configured to slide up and down along the vertical rails of the insert of FIG. 12.

FIG. 17 is a top view of a register configured to slide up and down along the vertical rails of the insert of FIG. 12 in accordance with another aspect of the present disclosure.

FIG. 18 is a perspective view of the register positioned in the insulated box as configured in FIG. 14.

FIG. 19 is a perspective view of the insulated box of FIG. 18 comprising the register and with a representation of ice packs placed over the register.

FIG. 20 is a perspective view of an assembled lid in accordance with another aspect of the present disclosure.

FIG. 21 shows a blank configured to be assembled into an inner piece of the lid of FIG. 19.

FIG. 22 shows a blank configured to be assembled into an outer piece of the lid of FIG. 19.

FIG. 23 is a perspective view of the lid of FIG. 19 in a partially assembled configuration.

FIG. 24 is a perspective view of the lid of FIG. 19 in another partially assembled configuration prior to one remaining step of pushing the inner piece of the lid into the outer piece of the lid such that tabs of the inner piece are secured by slots of the outer piece.

FIG. 25 is a perspective view of the insulated box covered by the lid.

DETAILED DESCRIPTION

The present disclosure can be understood more readily by reference to the following detailed description, examples, drawings, and claims, and the previous and following description. However, before the present devices, systems, and/or methods are disclosed and described, it is to be understood that this disclosure is not limited to the specific devices, systems, and/or methods disclosed unless otherwise specified, and, as such, can, of course, vary. It is also to be

understood that the terminology used herein is for the purpose of describing particular aspects only and is not intended to be limiting.

The following description is provided as an enabling teaching of the present devices, systems, and/or methods in its best, currently known aspect. To this end, those skilled in the relevant art will recognize and appreciate that many changes can be made to the various aspects of the present devices, systems, and/or methods described herein, while still obtaining the beneficial results of the present disclosure. It will also be apparent that some of the desired benefits of the present disclosure can be obtained by selecting some of the features of the present disclosure without utilizing other features. Accordingly, those who work in the art will recognize that many modifications and adaptations to the present disclosure are possible and can even be desirable in certain circumstances and are a part of the present disclosure. Thus, the following description is provided as illustrative of the principles of the present disclosure and not in limitation thereof.

As used throughout, the singular forms "a," "an" and "the" include plural referents unless the context clearly dictates otherwise. Thus, for example, reference to "an element" can include two or more such elements unless the context indicates otherwise.

Ranges can be expressed herein as from "about" one particular value, and/or to "about" another particular value. When such a range is expressed, another aspect includes from the one particular value and/or to the other particular value. Similarly, when values are expressed as approximations, by use of the antecedent "about," it will be understood that the particular value forms another aspect. It will be further understood that the endpoints of each of the ranges are significant both in relation to the other endpoint, and independently of the other endpoint.

For purposes of the current disclosure, a material property or dimension measuring about X or substantially X on a particular measurement scale measures within a range between X plus an industry-standard upper tolerance for the specified measurement and X minus an industry-standard lower tolerance for the specified measurement. Because tolerances can vary between different materials, processes and between different models, the tolerance for a particular measurement of a particular component can fall within a range of tolerances.

As used herein, the terms "optional" or "optionally" mean that the subsequently described event or circumstance can or cannot occur, and that the description includes instances where said event or circumstance occurs and instances where it does not.

The word "or" as used herein means any one member of a particular list and also includes any combination of members of that list. Further, one should note that conditional language, such as, among others, "can," "could," "might," or "may," unless specifically stated otherwise, or otherwise understood within the context as used, is generally intended to convey that certain aspects include, while other aspects do not include, certain features, elements and/or steps. Thus, such conditional language is not generally intended to imply that features, elements and/or steps are in any way required for one or more particular aspects or that one or more particular aspects necessarily include logic for deciding, with or without user input or prompting, whether these features, elements and/or steps are included or are to be performed in any particular aspect.

Disclosed are components that can be used to perform the disclosed methods and systems. These and other compo-

nents are disclosed herein, and it is understood that when combinations, subsets, interactions, groups, etc. of these components are disclosed that while specific reference of each various individual and collective combinations and permutation of these may not be explicitly disclosed, each is specifically contemplated and described herein, for all methods and systems. This applies to all aspects of this application including, but not limited to, steps in disclosed methods. Thus, if there are a variety of additional steps that can be performed it is understood that each of these additional steps can be performed with any specific aspect or combination of aspects of the disclosed methods.

FIG. 1 shows in one exemplary aspect an exterior piece 100 of an insulated box 2400 (shown in FIG. 25) in an unassembled configuration as a blank. As shown, the exterior piece 100 can comprise four subpanels 102a,b,c,d. Each subpanel can comprise a middle portion 110a,b,c,d, an upper portion 120a,b,c,d, and a lower portion 112a,b,c,d. The middle portions 110a,b,c,d can be joined by fold lines 124a,b,c. A side strip 128 can be joined to the fourth middle portion 110d by a fold line 127. The exterior piece 100 as a blank can define a planar first exterior surface 101, with a similar planar second exterior surface (not shown) opposite from the exterior surface 101.

Each middle portion 110a,b,c,d can be joined to an upper portion 120a,b,c,d by a fold line 125a,b,c,d. Each upper portion can comprise a connecting segment 121a,b,c,d and an end segment 122a,b,c,d. The end segments 122a,b,c,d can be joined to the connecting segments 121a,b,c,d by fold lines 130a,b,c,d.

The connecting segments 121a,c can be of various shapes, including rectangles, parallelograms, and trapezoids. In the current aspect, a first connecting segment 121a and a third connecting segment 121c can be trapezoidal in shape. The legs 126a,b,c,d of the first and third connecting segments 121a,c can form angles 123a,b,c,d with the fold lines 125a,b,c,d. The angles 123a,b,c,d can be about 45 degrees. A second and a fourth connecting segment 121b,d can be substantially rectangular and can comprise or define crease lines 132a,b,c,d.

Each end segment 122a,b,c,d can comprise a middle tab 134a,b,c,d and a side tab 136a,b,c,d. In the current aspect, the second and fourth end segments 122b,d can each comprise two side tabs 136a,b,c,d. The side tabs 136a,b,c,d can be joined to the middle tabs 134a,b,c,d by fold lines 138a,b,c,d. Each side tab can comprise a bottom edge 139a,b,c,d, and each bottom edge 139a,b,c,d can form an angle with the fold lines 138a,b,c,d. The lower portions 112a,b,c,d can be joined to the middle portions 110a,b,c,d by fold lines 140a,b,c,d.

FIG. 2 is a perspective view of the exterior piece 100 in an assembled configuration. The fold lines 140a,b,c,d joining the middle portions 110a,b,c,d to the upper portions 120a,b,c,d can form a top outside edge 210. The fold lines 140a,b,c,d joining the middle portions 110a,b,c,d to the lower portions 112a,b,c,d can form a bottom outside edge 220. The side strip 128 can be affixed to the first subpanel 102a by staples, hot melt glue, or other adhesives known in the art, or with no adhesive at all.

FIG. 3 shows an exemplary aspect of an insulator 300 that can be used in the insulated box 2400. The insulator 300 can form a loose fill (not shown) or another configuration known in the art. In the current aspect, the insulator 300 can comprise insulator pads 310. The insulator pads 310 can comprise a variety of materials known in the art, such as polystyrene and/or cellulose. The insulator pads 310 can comprise a bottom insulator 320 and side insulators 330a,

b,c,d. The side insulators 330a,b,c,d can comprise a first, second, third, and fourth side insulator 330a,b,c,d, respectively. The first and third side insulators 330a,c can be shorter than the second and fourth side insulators 330b,d. The side insulators can also comprise a single insulator pad (not shown) extending circumferentially around an interior piece 500.

The insulator pads 310 can comprise paper or other paper fiber materials; however, in other aspects, the insulation batts can comprise cotton, foam, rubber, plastics, fiberglass, mineral wool, or any other flexible insulation material. In the present application, the insulation batts can be repulpable. In the present aspect, the insulated box 2400 can be 100% recyclable. In the present aspect, the insulated box 2400 can be single-stream recyclable wherein all materials comprised by the insulated box 2400 can be recycled by a single processing train without requiring separation of any materials or components of the insulated box 2400. In the present aspect, the insulated box 2400 can be compostable. In the present aspect, the insulated box 2400 can be repulpable. In the present aspect, the insulated box 2400 and the insulator pads 310 can be repulpable in accordance with the requirements of the Aug. 16, 2013, revision of the "Voluntary Standard For Repulpaging and Recycling Corrugated Fiberboard Treated to Improve Its Performance in the Presence of Water and Water Vapor" provided by the Fibre Box Association of Elk Grove Village, Ill. which is hereby incorporated in its entirety. In the present aspect, the insulated box 2400 and the insulator pads 310 can be recyclable in accordance with the requirements of the Aug. 16, 2013, revision of the "Voluntary Standard For Repulpaging and Recycling Corrugated Fiberboard Treated to Improve Its Performance in the Presence of Water and Water Vapor" provided by the Fibre Box Association of Elk Grove Village, Ill.

Recyclable and repulpable insulation materials are further described in U.S. patent application Ser. No. 15/677,738, filed Aug. 15, 2017, U.S. Provisional Patent Application No. 62/375,555, filed Aug. 16, 2016, U.S. Provisional Patent Application No. 62/419,894, filed Nov. 9, 2016, and U.S. Provisional Patent Application No. 62/437,365, filed Dec. 21, 2016, which are each incorporated by reference in their entirety herein.

FIG. 4 is a perspective view of the partially assembled insulated box 2400. The insulator pads 310 are placed inside the assembled exterior piece 100. The bottom insulator 320 can cover, or proximately face, the lower portions 112a,b,c,d (not shown) of the exterior piece 100. The bottom insulator 320 can fully extend to the bottom outside edge 220. The side insulators 330a,b,c,d can alternate shorter and longer. For example, in the current aspect, the first side insulator 330a can be configured to proximately face the first middle portion 110a (not shown). Likewise, the second, third, and fourth side insulators 330b,c,d, respectively, can be configured to face the corresponding numbered middle portions 110b,c,d.

FIG. 5 shows the interior piece 500 of the insulated box 2400 in an unassembled configuration. The interior piece 500 can comprise a bottom panel 510, side panels 520a,b,c,d, and fold lines 530a,b,c,d joining the bottom panel 510 to the side panels 520a,b,c,d. An interior surface 502 faces out of the page in FIG. 5. Alternating side panels—for example, a first and a third side panel 520a,c—can comprise a middle tab 522a,b and a side tab 524a,b,c,d. The middle tabs 522a,b can be joined to the side tabs 524a,b,c,d by fold lines 526a,b,c,d. A second and a fourth side panel 520b,d can lack fold lines. The interior piece 500 can be formed from a

single flat piece with side panel cuts **540a,b,c,d** separating the side panels **520a,b,c,d** from each other. Thus, a blank of the interior piece **500** can be configured such that each side panel **520a,b,c,d** is not connected to any other side panel **520a,b,c,d**, except only indirectly through the bottom panel **510**. The side panel cuts **540a,b,c,d** can form angles with the fold lines **526a,b,c,d**, the angles being approximately 45 degrees.

FIG. 6 is a perspective view of the interior piece **500** with the fold lines **530a,b,c,d**; **526a,b,c,d** in a slightly bent configuration.

FIG. 7 is a perspective view of the interior piece **500** partially inside the partially assembled box of FIG. 4. The middle tab **522a** of the first side panel **520a** of the interior piece **500** can be configured to proximately face the first middle portion **110a** of the exterior piece **100**. Likewise, the second, third, and fourth side panels **520b,c,d** of the interior piece **500** can face the corresponding middle portions **110b,c,d** of the exterior piece **100**. Alternating side panels—for example, the second and fourth side panels **520b,d**—can be configured to extend completely between the second and fourth middle portions **110b,d** of the exterior piece **100**. The side tabs **524a,b,c,d** of the side panels **520a,c** can be configured to fold inwards toward a cavity **710** in the insulated box **2400**.

FIG. 8 is a perspective view of the partially assembled insulated box **2400**, showing a close-up of one of the exterior piece's **100** upper portions **120b** (of the exterior piece **100**) comprising an end segment **122b** comprising a side tab **136a**. The connecting segment can be configured to fold down toward the cavity **710** and cover a top edge **810** of the insulating pads **310**. In other aspects (not shown) in accordance with the present disclosure, the insulator pads can be omitted, in which case the insulating properties of air left behind in a space or gap left between the interior piece **500** and the exterior piece **100** can insulate the insulated box **2400**. In yet other aspects, at least a portion of the upper portion **120a,b,c,d** of the exterior piece **100**—not necessarily the connecting segment **121a,c**—can cover at least some portion of the space. In other words, “covering” can comprise “partially covering.”

The end segment **122b** can be configured to overlap or cover a top interior portion **820** of the assembled interior piece **500**. In some aspects, only a portion of the top interior portion **820** may be covered by a portion of the upper portion **120a,b,c,d** of the exterior piece **100**. The side tab **136a** can overlap the side panel adjoining the side panel overlapped by the end segment **122b**, which in this aspect can be side panel **520a**.

FIG. 9 is a perspective view of the partially assembled insulated box **2400**, showing the next step in assembly after FIG. 8. The upper portion **120a** can be configured to fold down toward the cavity **710**. The connecting segment **121a** can overlap a corner **910** of the adjoining connecting segment. The end segment **122a** can overlap the top interior portion **820** of the interior piece **500** and further overlap the side tab **136a** of the exterior piece **100**. The end segments **122a** can be affixed in place by adhesives known in the art or by friction without adhesive.

FIG. 10 shows the insulated box **2400** after the step shown in FIG. 9 has been completed. The end segment **122a** overlaps side panel **520a** and side tab **136a** of the exterior piece **100**.

FIG. 11 shows another view of the insulated box **2400**, particularly a close-up of end segment **122b**.

FIG. 12 is a top view of a box insert **1200** with vertical rails **1220** in a flat configuration. The box insert **1200** can

comprise a center segment **1210** and vertical rails **1220a,b,c,d,e,f** joined thereto by fold lines **1230a,b,c,d,e,f**. The center segment **1210** can comprise cutouts **1240a,b,c,d,e,f**. An edge **1242a,b,c,d,e,f** of each cutout **1240a,b,c,d,e,f** can be contiguous with an edge **1222a,b,c,d,e,f** of each vertical rail **1220a,b,c,d,e,f**, respectively. The edges **1242a,b,c,d,e,f** of the cutouts **1240a,b,c,d,e,f** can be curvilinear, rectilinear, or some other shape. The edges **1222a,b,c,d,e,f** of the vertical rails **1220a,b,c,d,e,f** can be curvilinear or rectilinear or some other shape.

FIG. 13 is a perspective view of the box insert **1200**. The vertical rails **1220a,b,c,d,e,f** of the box insert **1200** can be configured to bend upward along the fold lines **1230a,b,c,d,e,f**. As shown in the current aspect, the fold lines **1230a,b,c,d,e,f** between the vertical rails **1220a,b,c,d,e,f** and the center segment **1210** can coincide with the fold lines **530a,b,c,d** between the bottom panel **510** and the side panels **520a,b,c,d** of the interior piece **500**.

FIG. 14 is a perspective view of the box insert **1200** inside the insulated box **2400**. The cutouts **1240a,b,c,d,e,f** can be configured to expose regions of a bottom **1410** of the cavity **710**. The box insert **1200** can be configured to allow air to flow to and from the cutouts **1240a,b,c,d,e,f** and spaces **1420a,b,c,d,e,f** between the vertical rails. The vertical rails **1220a,b,c,d,e,f** can be configured to extend to the top interior portion **820**.

FIG. 15 is a perspective view of the box insert **1200** in another exemplary aspect. In the current aspect, the vertical rails **1220a,b,c,d,e,f** can be configured to rise to a height **1510** below the top interior portion **820**. The vertical rails **1220a,b,c,d,e,f** can also be configured to adjoin each other at bottom corners **1520a,b,c,d**—without a space **1420** between them.

FIG. 16 is a top view of a register **1600**. The register **1600** can comprise a face segment **1602**. The face segment **1602** can comprise holes **1610a,b,c,d**; side cutouts **1620a,b,c,d,e,f**; and corner cutouts **1630a,b,c,d**. The register can be cut from a single flat piece.

FIG. 17 is a top view of a register **1700** in another exemplary aspect. The register **1600** can further comprise side segments **1700a,b,c,d** joined to the face segment **1602** by fold lines **1720a,b,c,d**. The side segments **1700a,b,c,d** can comprise fold lines **1712a,b,c,d** configured to be parallel to the corresponding fold lines **1720a,b,c,d**.

FIG. 18 is a perspective view of the box insert **1200** receiving the register **1600**. The register **1600** and the box insert **1200** can together form a registration system **1800**. The registration system **1800** can be configured to allow the register **1600** to slide up and down the vertical rails **1220a,b,c,d,e,f** along a vertical axis **1820** while the face segment **1602** is maintained in a horizontal plane **1810**. The center segment **1210** can be configured to cover a bottom interior of the box **2400**, and one or more of the vertical rails **1220a,b,c,d,e,f** can be configured to cover a side interior of the box **2400**. The register **1600** can be configured to slidably move along one or more of the vertical rails **1220a,b,c,d,e,f** while maintaining a horizontal position, and the cutout **1620a,b,c,d,e,f** of the register **1600** can be configured to surround one or more of the vertical rails **1220a,b,c,d,e,f** of the box insert **1200**.

FIG. 19 is a perspective view of the registration system **1800**. The side cutouts **1620a,b,c,d,e,f** can be configured to receive the vertical rails **1220a,b,c,d,e,f** such that the register **1600** does not tip over when an overhead weight **1910a,b** is placed near an edge **1920** of the face segment **1602** or when

the register 1600 is not supported under a center of mass (not shown) of the register 1600 with the overhead weight 1910a,b.

FIG. 20 is a perspective view of a lid 2000 for the insulated box 2400. The lid 2000 can comprise an inner piece 2010 and an outer piece 2020.

FIG. 21 is a top view of the inner piece 2010 of the lid 2000 in a flat, unassembled configuration. The inner piece 2010 can comprise a center segment 2110 and side segments 2120a,b,c,d joined to the center segment 2110 by fold lines 2130a,b,c,d. The fold lines 2130a,b,c,d can comprise tab cuts 2140a,b,c,d,e,f,g,h.

FIG. 22 is a top view of the outer piece 2020 of the lid 2000 in a flat, unassembled configuration. The outer piece 2020 can comprise a center segment 2210, connecting segments 2220a,b,c,d joined to the center segment 2210 by fold lines 2215a,b,c,d, and end segments 2230a,b,c,d joined to the connecting segments 2220a,b,c,d by fold lines 2225a,b,c,d. The fold lines 2225a,b,c,d can be double fold lines. Alternating segments, such as a first and a third connecting segment 2220a,c, can comprise side tabs 2222a,b,c,d joined to the connecting segments 2220a,c by fold lines 2224a,b,c,d. The fold lines 2215a,b,c,d joining the center segment 2210 to the connecting segments 2220a,b,c,d can comprise or define slots 2216a,b,c,d,e,f,g,h. The end segments 2230a,b,c,d can comprise tab slots 2232a,b,c,d,e,f,g,h and tabs 2234a,b,c,d,e,f,g,h. Any one or more of the fold lines disclosed herein can be defined by the parts joined by or at the corresponding fold line(s).

FIG. 23 is a perspective view of a partially-assembled lid 2000. The lid 2000 can further comprise an insulator such as an insulating pad 2310 between the outer piece 2020 and the inner piece 2010. The side segments 2120a,b,c,d of the inner piece 2010 can fold toward a cavity 2320 of the outer piece 2020 in an assembled configuration. Folding the side segments 2120a,b,c,d in this way can expose the tabs 2330a,b (and others not shown) formed by the tab cuts 2140a,b,c,d,e,f,g,h. The tabs 2330a,b can be received by the tab slots 2232a,b,c,d,e,f,g,h such that the insulating pad 2310 and the inner piece 2010 are secured. The outer piece 2020 can be assembled by sandwiching the side tabs 2222a,b,c,d between neighboring connecting segments 2220b,d and end segments 2230b,d.

FIG. 24 shows another perspective view of the inner piece 2010 with its side segments 2120a,b,c,d folded into the outer piece 2020, the inner piece 2010 ready to be pushed in, locking the tabs 2330a,b,c,d,e,f,g,h of the inner piece 2010 into the tab slots 2232a,b,c,d,e,f,g,h of the outer piece 2020 (shown in FIG. 22).

FIG. 25 shows the assembled insulated box 2400 covered by the lid 2000.

The interior piece 500 and the exterior piece 100 of the insulated box 2400, the register 1600, the box insert 1200 with vertical rails 1220, and the inner piece 2010 and the outer piece 2020 of the lid 2000 can each be formed from a single piece of flat material, such as solid cardboard, corrugated cardboard, corrugated plastic, and other materials known in the art. The box insert 1200 with vertical rails 1220 can also be used with or without the register 1600 to maintain a uniform temperature and humidity level within the insulated box 2400. The spaces 1420 between the vertical rails 1220, the cutouts 1620 exposing the bottom 1410 of the cavity 710, and the holes 1610 in the register 1600 can all facilitate air flow and by diffusion and convection.

The registration system 1800 can be configured to place perishable items such as food (not shown) on one side of the

register 1600 and a heat transfer element such as an ice pack (not shown) on the other. The ice pack can be placed above the food to allow cooling by cold air flowing downward. Multiple registers 1600 can be used.

One should note that conditional language, such as, among others, “can,” “could,” “might,” or “may,” unless specifically stated otherwise, or otherwise understood within the context as used, is generally intended to convey that certain aspects include, while other aspects do not include, certain features, elements and/or steps. Thus, such conditional language is not generally intended to imply that features, elements and/or steps are in any way required for one or more particular aspects or that one or more particular aspects necessarily include logic for deciding, with or without user input or prompting, whether these features, elements and/or steps are included or are to be performed in any particular aspect.

It should be emphasized that the above-described aspects are merely possible examples of implementations, merely set forth for a clear understanding of the principles of the present disclosure. Any process descriptions or blocks in flow diagrams should be understood as representing modules, segments, or portions of code which include one or more executable instructions for implementing specific logical functions or steps in the process, and alternate implementations are included in which functions may not be included or executed at all, may be executed out of order from that shown or discussed, including substantially concurrently or in reverse order, depending on the functionality involved, as would be understood by those reasonably skilled in the art of the present disclosure. Many variations and modifications may be made to the above-described aspect(s) without departing substantially from the spirit and principles of the present disclosure. Further, the scope of the present disclosure is intended to cover any and all combinations and sub-combinations of all elements, features, and aspects discussed above. All such modifications and variations are intended to be included herein within the scope of the present disclosure, and all possible claims to individual aspects or combinations of elements or steps are intended to be supported by the present disclosure.

That which is claimed is:

1. A lid, comprising:
an outer piece comprising an end segment comprising an outer tab received in a tab slot of the outer piece;
an inner piece separate from the outer piece and defining an inner tab positioned inside the outer piece, the inner piece and the outer piece defining a space therebetween; and
a repulpable insulator pad within the space.

2. The lid of claim 1, wherein the outer piece further comprises an outer center segment and the inner piece further comprises an inner center segment.

3. The lid of claim 1, wherein the inner piece comprises an inner center segment and an inner rim comprising a plurality of side segments joined to the inner center segment by a plurality of fold lines.

4. The lid of claim 3, wherein each fold line in the plurality of fold lines comprises a tab cut and the inner tab.

5. The lid of claim 1, wherein the outer piece further comprises an outer center segment and an outer rim comprising a plurality of connecting segments joined to the outer center segment by fold lines defining slots.

6. The lid of claim 5, wherein the outer rim comprises alternating side tabs joined to the plurality of connecting

11

segments by fold lines, wherein a first connecting segment and a third connecting segment of the outer rim comprise side tabs.

7. The lid of claim 5, wherein the outer piece further comprises end segments joined to the plurality of connecting segments by fold lines, each end segment comprising the outer tab and the tab slot.

8. The lid of claim 7, wherein the fold lines are double fold lines.

9. The lid of claim 7, wherein the inner tab of the inner piece is locked into the tab slot of the outer piece.

10. The lid of claim 1, wherein the repulpable insulator pad and the inner piece are secured within the space defined between the inner piece and the outer piece when the outer tab is received in the tab slot of the outer piece.

11. The lid of claim 10, wherein the outer tab is sandwiched between a connecting segment and the end segment.

12. A method of assembling a lid, comprising:

arranging an outer piece comprising an outer center segment and an outer rim comprising an outer tab received in an outer tab slot and defining a space of the outer center segment within the outer rim;

12

5 placing a repulpable insulator pad within the space of the outer center segment of the outer piece; and covering the space comprising the repulpable insulator pad with an inner piece that is separate, and an inner tab of the inner piece that defines the space from the outer piece, the inner piece comprising an inner center segment, and an inner rim.

10 13. The method of claim 12, further comprising assembling the outer piece by sandwiching a plurality of side tabs between a plurality of neighboring connecting segments and end segments.

14. The method of claim 12, further comprising folding side segments of the inner piece fold toward a cavity of the outer piece to expose the inner tab formed by a tab cut.

15 15. The method of claim 14, further comprising receiving the inner tab of the inner piece into the outer tab slot of the outer piece to secure the inner piece to the outer piece.

16. The method of claim 12, further comprising securing the repulpable insulator pad and the inner piece within the space defined between the inner piece and the outer piece when the outer tab is received in the outer tab slot of the outer piece.
